UNITED STATES PATENT OFFICE.

BIRGER LJUNGSTRÖM, OF STOCKHOLM, SWEDEN.

TURBINE.

No. 906,244.

Specification of Letters Patent.

Patented Dec. 8, 1908.

Application filed February 23, 1907. Serial No. 358,963.

To all whom it may concern:

Be it known that I, BIRGER LJUNGSTRÖM, a subject of the King of Sweden, residing at 8 Flemminggatan, Stockholm, Sweden, have 5 invented certain new and useful Improvements in Gas-Turbines; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 This invention relates to radial flow turbines and is designed to render them more compact in order not only to diminish the leakage but also to make it possible to manufacture turbines of great speed.

20 In the accompanying drawings Figure 1 is a vertical longitudinal section of a radial turbine. Fig. 2 is a longitudinal section of a compound or dual stage radial turbine. Fig. 3 is a part of the vane rings in vertical 25 transverse section. Fig. 4 is a vertical section of a vane ring, and Fig. 5 illustrates a modified form.

In order to attain the fullest and most 30 economical expansion of the fluid it is necessary with these turbines that the fluid passes through a large number of cylindrical vane-rings placed outside of or threaded into each other and divided alternately into two series rotating relatively to each other.

35 Such turbines offer, theoretically, important advantages in several ways over axial flow turbines but have not been used to any great degree on account of the difficulties of construction connected therewith. Most prominent of all the difficulties are those connected 40 with the vane-rings. The number of vane-rings is determined by the peripheral speed which may be given them without causing too great centrifugal strains. With the sys-

45 tems of construction now used, especially with high expansion of the elastic fluid and large circuit areas, the vanes must be constructed of comparatively great width, that is to say, they occupy a large space in a radial 50 direction. A radial flow turbine constructed with such vanes must necessarily be of large diameter and slow speed, as owing to conditions of strength a certain peripheral speed must not be exceeded. This not only renders the turbine much more expensive but also increases the cost of the dynamo driven

thereby when such is used. These drawbacks are, however, not the only ones nor perhaps even the most important. Owing to the large diameter required the length of the 60 leakage slots past the vane-edges and packing-rings is increased in the same proportion the consequence being that the leakage is still further increased on account of the large free space which is required by the 65 large dimensions and necessitated by their greater change of form on being heated. This loss by leakage has proved to be particularly prejudicial in turbines of small power. In order to overcome these disadvantages it 70 has for example been constructed as a radial flow turbine composed of several radial turbines of medium diameter placed axially behind each other, through which the steam must pass in series in order to attain the 75 necessary expansion. Besides great complexity further losses arise on transferring the fluid from one turbine to the other. These latter losses as well as those due to leakage indicated in connection with the 80 single radial flow turbine may be avoided without dividing the turbine into several turbines, if vanes of sufficient strength are constructed with such small radial extension, that the necessary number of vanes can be 85 accommodated in a single radial flow turbine of small diameter.

The present invention comprises a method of constructing such vane series enabling the use of single, radial turbines of great 90 efficiency and small diameter, even with high power and with great decrease of volume, weight and cost of manufacture. It is obvious for instance in the case of radial marine turbines where the number of revolutions for various reasons must be very 95 low, that great advantages with regard to diameter, weight and cost may be attained by such vane-series, even when a division of the turbine into high-pressure and low-pressure turbines on the same or on different propeller shafts must be resorted to.

As shown in Figs. 3, 4 and 5 of the annexed drawing according to the present invention the vane-rings are not divided but are 105 formed as complete rings with the vanes divided into two or more lengths with the cross section bent in the same direction, and supported by intermediate complete carrier or fastening rings, which are formed 110 in one continuous piece with the vane ends or otherwise firmly connected thereto and

therefore need not project outside or inside the inner or outer edge of the vanes. In this manner durable vane disks or drums are constructed having a very slight radial expansion and at the same time small diameter and large circuit-area is obtained.

In connection herewith it may be pointed out, that the inventor is aware that turbines have been previously constructed with vane rings placed in alinement and provided with concentric fastenings. This arrangement however has no reducing effect on the diameter as the latter may in such an arrangement be chosen according to the length of the turbine as desired. This reduction of diameter and consequent decrease in losses due to leakage or transfer which as above said are obtained by applying the said arrangement to radial flow turbines, therefore comprises that new technical effect which is aimed at by the present invention and which is not obtained by the above named arrangement. Centrifugal strains in the vanes of an axial turbine may in addition be taken up by the connections or fastenings alone and need not, as in the case of radial turbines, cause bending strains and consequent division into several lengths with interposed strengthening rings.

On Fig. 1 the stationary vanes 5 and the rotating vanes 6 consist of perforated cylinders constructed as aforesaid and threaded into each other.

Fig. 2 shows a marine turbine with two expansion chambers, constructed according to the same principle, wherein, as in Fig. 1 the stationary and the rotating vane-cylinders 15 and 16 respectively are fastened to

flat or plane disks. The stationary cylinders 15 are not placed directly on the turbine 40 casing but on separate or independent plates 17.

In Figs. 3 and 4 the vanes 1 and rings are made in one piece while in Fig. 5, I have shown four separate vane rings 2^a each 45 having a separate series of vanes 1^a. These rings 2^a are angular in cross section so that when several rings are assembled their flanges interlock and form a composite stiff vane-ring.

I claim:

1. In a radial turbine vanes united in rings, said vanes being divided in lengths by means of rings intermediate the vane ends.

2. In a radial turbine vanes united in rings, said vanes being divided in lengths by means of carrying rings intermediate the vane ends, said rings being rigidly secured to said vanes.

3. In a radial turbine vanes united in rings, said vanes being divided in lengths by means of rings intermediate the vane ends, said ends being connected to each other.

4. In a radial turbine vanes united in rings, said vanes being divided in lengths by means of rings intermediate the vane ends, said ends being connected to each other by means of rings.

In testimony, that I claim the foregoing 70 as my invention, and have signed my name in presence of two subscribing witnesses.

BIRGER LJUNGSTRÖM.
